SAFETYPIN

Henry Van Campen, New York, N. Y.

Application November 5, 1943, Serial No. 509,030

3 Claims. (Cl. 24—156)

This invention has general reference to safety pins and comprehends an improvement in this class of pins by virtue of which the safety factor thereof is materially increased while rendering the pin capable of use for effectively pinning together relatively different thicknesses of materials.

The invention is directed more particularly to an improved head structure for safety pins which is so constructed and arranged as to provide a plurality of terminal hooks disposed in reversely arranged spaced nested relation to define a multiplicity of catches, one enclosed by the other whereby accidental displacement of the terminal of the piercing leg from the innermost terminal hook, when engaged therewith, will result in a subsequent automatic engagement thereof with the next adjacent outer catch or hook.

A further feature of the head construction heretofore described renders the pin capable of multiple use by extending or increasing its range or capacity, as it is apparent that by selectively engaging the piercing leg with the several hooks or catches, the distance between the legs of the pin when engaged will vary to render the pin capable of accommodating varying amounts of material pinned thereby.

A pin embodying the above improvements can be produced without appreciably adding to the amount of material usually required or materially increasing the cost and selling prices thereof.

With the above enumerated and other objects in view, the invention is set forth in greater detail in the following specification and particularly pointed out in the appended claims, while the same is illustrated in the accompanying drawing, wherein:

Fig. 1 is a perspective view of a safety pin constructed in accordance with the present invention.

Fig. 2 is an enlarged vertical sectional view through the head of the pin, taken approximately on the line 2—2 of Fig. 1, showing the piercing leg engaged with the inner hook or catch.

Fig. 3 is a similar view illustrating the piercing leg engaged with the outer hook or catch.

Fig. 4 is a perspective view illustrating a modified form of the invention.

Referring to the drawing by characters of reference, the pin which is fashioned from a length of resilient wire is formed to provide an intermediate coiled portion 10 and a pair of normally divergent legs 11 and 12 extending tangentially therefrom in the same general direction and tensioned against movement of the free ends thereof toward each other. The leg 12 which is here-

inafter designated the piercing leg is formed with a pointed terminal 13 at the free end thereof which is adapted to engage with a head or keeper element 14 secured to the free end of the other leg 11. The head 14 which is constructed of sheet material is bent and formed to provide a pair of leaves 15 and 16 extending from said leg 11 in the direction of the other leg and arranged in spaced side-by-side relation. The leaves 15 and 16 are formed with reversely arranged spaced concentric arcuate terminals 17 and 18 nested or arranged one within the other to provide hooks or catches with which the pointed terminal 13 of the piercing leg 12 is adapted to be selectively engaged for retention thereby due to the inherent tendency of said piercing leg to move in a direction toward said arcuate terminals. From the foregoing construction, it will be observed that the hooked terminals 17 and 18 are provided with entrance mouths 19 and 20 which face toward the head supporting leg 11 but which are separated from each other and lie on opposite sides of the leaf 15. It thus follows that when the pointed terminal 13 of the piercing leg 12 is engaged with the innermost hook or catch 17, the leg 12 must be moved toward the leg 11 against the tension, then shifted laterally after passing through the entrance mouth 19 thence between the outer surface of the inner catch and the inner surface of the outer catch 18, after which said leg 12 is shifted laterally after passing through the entrance mouth 20 of the outer catch, in order to disengage the piercing leg 12 from the head 14 of the pin. It will also be observed that this increases the safety factor due to the fact that if the piercing leg should be accidentally released from the inner catch 17, it will be caught by the outer catch 18.

It is apparent that when the piercing leg 12 is engaged with the outer catch 18, it will be spaced a greater distance from the head supporting leg 11 than when the piercing leg is engaged with the inner catch 17, hence this varies the range or capacity of the pin so that when it is engaged in the outer catch it will accommodate a greater amount of material to be pinned than when it is engaged with the inner catch.

In the modified form of the invention illustrated in Fig. 4 of the drawing, the construction of the head or keeper element is substantially identical with that of the preferred form, with the exception that in this instance an additional leaf 25 is employed which is secured to the leg 11 and extends therefrom in the direction of the piercing leg. The leaf 25 is arranged in side-by-side relation to the leaf 15 and is

formed with an arcuate terminal 26 disposed in spaced concentric nested relation to the arcuate terminal 18 and defines an entrance mouth 27 facing toward the supporting leg 11 on the opposite side of the head from the entrance mouth 20 and separated from the entrance mouth 19 by the leaf 16.

What is claimed is:

1. A safety pin including a pair of connected legs tensioned for normal relative separation of the free ends thereof, one of said legs constituting a piercing leg having a pointed extremity a head secured to the free end portion of the other leg and constructed to provide a pair of leaves extending from said leg in the direction of the other leg and arranged in spaced side-by-side diverging relation, said leaves having reversely arranged spaced concentric arcuate terminals defining retaining hooks nested one within the other and with which inner hook the pointed extremity of the piercing leg can only be engaged and disengaged by passage of said extremity through the outer hook, the tension of said legs being adapted to normally urge the piercing leg extremity into engagement with one of said hooks when the same is engaged with the head.

2. In a safety pin, a length of resilient wire formed to provide a coiled intermediate portion and a pair of normally divergent legs extending therefrom in the same general direction and tensioned against movement of the free ends thereof toward each other, a pointed terminal at the free end of one leg and a head secured to the free end portion of the other leg constructed to provide a pair of leaves extending from said leg in the direction of the other leg and arranged in spaced side-by-side relation, said leaves hav-

ing reversely arranged spaced concentric arcuate terminals defining retaining hooks nested one within the other and with which the pointed terminal of the piercing leg is adapted to be selectively engaged and retained by the tendency of said leg terminals to normally separate, said piercing leg terminal being engageable with the inner hook and disengageable from the head only after passing of the same under the outer hook.

3. In a safety pin, a length of resilient wire formed to provide a coiled intermediate portion and a pair of normally divergent legs extending therefrom in the same general direction and tensioned against movement of the free ends thereof toward each other, a pointed terminal at the free end of one leg to constitute a piercing leg and a sheet of material fashioned to provide a head having a tubular intermediate portion secured in surrounding relation to the free end portion of the other leg and including a pair of substantially flat leaves one of which is disposed in a plane which extends approximately between the legs and the other of which leaves diverges from said plane, reversely arranged spaced arcuate hooked portions at the free edges of said leaves, the hooked portion of the first mentioned leaf being located within the hooked portion of the other leaf so that the piercing leg is engaged and disengaged from the inner hooked portion of the head by compound successive inward and lateral springing movements of the same against the inherent tendency of the same to move directly away from the other leg and whereby the pointed extremity of said piercing leg can only be engaged and disengaged by the passage of said extremity under the outer hooked portion of the head.

HENRY VAN CAMPEN.
